UNITED STATES PATENT OFFICE.

ANDREW OLSEN, OF CLEVELAND, OHIO, ASSIGNOR TO THE CLEVELAND FOLDING MACHINE COMPANY, OF CLEVELAND, OHIO, A CORPORATION OF OHIO.

FOLDING-MACHINE.

1,191,819.

Specification of Letters Patent. Patented July 18, 1916.

Application filed April 4, 1914. Serial No. 829,635.

To all whom it may concern:

Be it known that I, ANDREW OLSEN, a subject of the King of Sweden, residing at Cleveland, in the county of Cuyahoga and 5 State of Ohio, have invented certain new and useful Improvements in Folding-Machines, of which the following is a specification.

My invention relates to improvements in 10 folding machines, and more particularly to certain details thereof, which secure accuracy and smooth, even folds in the paper folded thereby. These improvements are applicable to mechanism forming the right 15 angle fold, although they are not necessarily limited thereto.

In folding the right-angle folds, especially with the machine operating at high speed, it is commonly found that diagonal creases, 20 are formed at the folded edges, which, of course, mar the complete signature or folded sheet. Moreover, the lighter paper stock, when passed into the folding plate against its stops, not infrequently is found to slip 25 slightly out of register or alinement, and in consequence the edges of the completed signature or folded sheet are at a slight angle with each other.

Accordingly, I have invented certain simple devices or adjuncts for the folding machine hereinafter explained, which serve to correct the difficulties just referred to. Briefly, these comprise a guide suitably positioned before the right-angle buckling and 35 folding rolls of the folding machine, which includes resilient means for expelling the air from the plies of the folded sheet; this being the common cause for diagonal wrinkles therein. There are also associated with the side plate of the right-angle folding mechanism, a plurality of laterally acting springs which serve to hold the folded sheet in position therein with its surfaces in close engagement, but said springs are herein 40 claimed only in combination with other features of my invention.

These improvements are hereinafter described and shown in detail in connection with sufficient of the folding machine mechanism to make their operation and construction perfectly clear.

Referring to the accompanying drawings, Figure 1 illustrates the side plate, together with co-acting folding and buckling rolls,

equipped with my improvements. Fig. 2 is 55 a diagram showing the course of the paper from the folding machine into said side plate and the relation of the various parts. Fig. 3 is an enlarged detail of the inverted guide, shown partially broken away to exhibit the springs. Fig. 4 is another detail showing the position of the springs within the side plate, and Fig. 5 is an end view of a folding machine to which my improvements are applicable; the same being centrally broken away and briefly described for illustrating the general purpose of my invention.

Throughout the several figures of the drawings, I have employed the same character of reference to indicate similar parts.

These improvements are applicable to the folding machine set forth in application for United States Letters Patent, Serial No. 824,238, filed March 12, 1914, although they 75 are not limited thereto.

Referring first to Fig. 5, the course of the paper through the folding machine may be traced, in order to afford an initial idea of the present improvements and their purpose. 80 Assuming that the paper has received its primary transverse fold or folds, it is passed to the vertical frame *a* from between paired rolls *b*, *b'*; the rear co-acting rolls of each pair being hidden. From the frame *a*, the 85 paper is passed to the right into the folding plate *c*, by means of the two sets of inclined vertical rolls *d*, *e*, which co-act with the guide *o* to support and advance the paper for its right angle fold. The folding plate *c* is 90 set at an angle of 45 degrees with the transverse travel of the paper, to which it is passed through the V-shaped guide *f* by the buckling rolls *g*, *h*, until engaged with a stop *c'* (see diagram Fig. 2), when the folding rolls *h*, *i*, seize the paper 1 to make a 95 right-angle fold. Inasmuch as my improvements primarily reside in the spring-pressed guide of Fig. 3, further details of the folding machine mechanism need not be explained.

The guide *f* is removably positioned rearwardly of the rolls *g*, *h*, between which it directs the folded sheet. The two walls *j*, *j'* of the guide are converging, and a 105 continuous series of sectional leaf-springs *j''* are riveted to one member thereof and bear lightly against the opposing member.

It is obvious that a single transversely-slotted spring of analogous construction might be substituted for the several sectional springs *j*'.

- 5 The bar *c*'' is adjustably mounted upon the side plate by means of screws insertible in the rows of tapped holes at top and bottom, so that the bowed springs *k*, which extend through the slots in said side plate, 10 may lie in the path of the folded sheet 1. The gage or thickness of these springs is somewhat exaggerated (Fig. 4) for the purpose of illustration, but they are tensioned to bear upon the inserted portion of the 15 folded sheet and hold it in alinement with the remainder of the sheet between the rolls; said springs being readily deflected for the purpose of permitting the passage of the paper into and out of the side plate. The 20 position of the supporting bar *c*'' and its attached springs *k*, together with the stops *c*', may be varied to suit the length of the folded sheet which is passed through the side plate, and the right-angle fold *l*' which 25 is to be made.

It will be understood that as the folded sheets pass beneath the spring sections of the guide *f*, the air will very readily be expelled from between the adjacent surfaces 30 of the paper, hence no appreciable amount of air will remain therebetween to cause wrinkles as the paper passes between rolls *g*, *h*. As the paper passes within the side plate, it engages the bowed springs *k*, which 35 serve to maintain it in position with its surfaces pressed closely together, thereby overcoming the natural resiliency of the paper and preventing the entrance of any appreciable amount of air between its surfaces. 40 A plurality of spaced, adjustable springs preferably are employed for this purpose, which also serve to maintain the sheet in alinement while traveling into and out of the side plate, preliminary to completing the 45 right-angle fold.

Having now described the preferred embodiment of my invention, I claim as new and desire to secure by Letters Patent, the following:—

- 50 1. In a folding machine, the combination with paired rolls, of a guide associated therewith, through which the paper is adapted to be passed to said rolls, and resilient means within the guide for expelling the air from 55 between the folded plies of the sheet, substantially as set forth.
2. In a folding machine, the combination with folding rolls, of a guide positioned before said rolls, through which the sheet is 60 adapted to be passed thereto, and a plurality of spring-members engaging the folded sheet substantially throughout its entire width, and adapted to expel the air from

between its folded plies, substantially as set forth.

3. In a folding machine, the combination with right-angle folding and sheet-passing rolls, of a guide through which the sheet is directed to said rolls, and a series of light springs presenting substantially continuous 70 surfaces adapted to bear upon the sheet and expel the air from between its folded plies, substantially as set forth.

4. In a folding machine, the combination with the right-angle folding-mechanism, of 75 a guide in advance thereof, resilient air-expelling means adapted to engage the paper, an associated side-frame and a plurality of spaced spring-members therein laterally bearing against the paper and adapted to maintain it in closely folded condition, substantially as set forth.

5. In a folding machine, the combination with right-angle folding mechanism, comprising folding and buckling rolls and associated air-expelling mechanism, of a side plate positioned adjacent thereto, a paper stop therein, and an adjustable spring mechanism associated with said side plate and adapted to bear upon the folded sheet and 90 maintain its surfaces in engagement while said sheet is traveling therein, substantially as set forth.

6. In a folding machine, the combination with co-acting paired rolls, of a guiding 95 member adapted to direct the paper between said rolls, and resilient means associated with said member and engaging the sheet substantially throughout a given plane for expelling the air from between the folded 100 plies or surfaces of the sheet prior to its entrance between the rolls, substantially as set forth.

7. In a folding machine, the combination with co-acting rolls, of a guide for directing 105 the sheets therebetween, and resilient pressure-means adapted to bear upon the sheet approximately at all points along its width for expressing the air from between the plies of the sheet prior to its insertion between 110 the co-acting rolls, substantially as set forth.

8. In a paper folding machine, the combination with co-acting rolls, of means for advancing folded sheets thereto, and air-expelling means adapted to act substantially 115 throughout the width of the sheet; the same being positioned immediately before said rolls for forcing the air from between the plies of the sheet, substantially as set forth.

In testimony whereof I do now affix my 120 signature in the presence of two witnesses.

ANDREW OLSEN.
